UNITED STATES PATENT OFFICE

166,905

DRAFTSMAN'S INSTRUMENT

Sydney N. Coates, Seattle, Wash.

Application March 24, 1952, Serial No. 19,031

Term of patent 14 years

(Cl. D52—1)

To all whom it may concern:

Be it known that I, Sydney N. Coates, a citizen of the United States of America, residing at Seattle, in the county of King and State of Washington, have invented a new, original, and ornamental Design for a Draftsman's Instrument, of which the following is a specification, reference being had to the accompanying drawing, forming a part hereof.

I claim:

The ornamental design for a draftsman's instrument, as shown.

SYDNEY N. COATES.
